LAMPPOST

Jozsef Molnar, 158 Maple Ave., Holmes, Pa.

Filed Feb. 27, 1962, Ser. No. 69,006

Term of patent 14 years

(CL. D48—31)

I claim:

The ornamental design for a lamppost, as shown and described.
